UNITED STATES PATENT OFFICE.

LARS V. HULT, OF CHICAGO, ILLINOIS.

DESIGN FOR A BRACKET BACK FOR LIGHTING FIXTURES.

Application filed February 18, 1925. Serial No. 12,419. Term of patent 3½ years.

To all whom it may concern:

Be it known that I, LARS V. HULT, a citizen of the United States, residing at Chicago, in the county of Cook and State of Illinois, have invented a new, original, and ornamental Design for Bracket Backs for Lighting Fixtures, of which the following is a specification, reference being had to the accompanying drawing, forming part thereof.

In the drawing, Figure 1 shows my design for a bracket back for lighting fixtures in front elevation, while Figure 2 shows a side view thereof.

I claim;

The ornamental design for a bracket back for lighting fixtures, as shown.

LARS V. HULT.
